The ornamental design for a vehicle hood, as shown and described.

(22) Filed: **Oct. 8, 2015**

(30) **Foreign Application Priority Data**

DESCRIPTION

Apr. 9, 2015 (EM) 002678284-0001

FIG. 1 is a top, front, left side perspective view of a vehicle hood showing my new design;

(51) **LOC (10) Cl.** **12-08**

FIG. 2 is a front side view thereof;

(52) **U.S. Cl.**

FIG. 3 is a left side view thereof;

USPC **D12/173**

FIG. 4 is a rear side view thereof;

(58) **Field of Classification Search**

FIG. 5 is a right side view thereof;

USPC D12/171, 173; 293/89.16, 89.17

FIG. 6 is a top plan view thereof; and,

CPC B60R 2021/343; B60R 21/34; B62D 25/12

FIG. 7 is a bottom plan view thereof.

See application file for complete search history.

The broken lines in the drawing views are included for the purpose of illustrating portions of a vehicle hood only, and form no part of the claimed design.
